UNITED STATES PATENT OFFICE.

AARON A. ACKERLY, OF CHICAGO, ILLINOIS.

STEAM-ENGINE CUT-OFF VALVE.

SPECIFICATION forming part of Letters Patent No. 288,196, dated November 13, 1883.

Application filed April 2, 1883. (No model.)

To all whom it may concern:

Be it known that I, AARON A. ACKERLY, residing at Chicago, in the county of Cook and State of Illinois, and a citizen of the United States, have invented new and useful Improvements in Steam-Engine Cut-Off Valves, of which the following is a full description, reference being had to the accompanying drawings, in which—

10 Figure 1 is a vertical longitudinal section. Fig. 2 is a detail; Fig. 3, a detail. Fig. 4 is a detail, showing a check-valve at the exhaust-port H.

15 In using steam expansively as a motive power with high-pressure engines it is common to use a slide or rotary valve arranged to close the exhaust-ports at about the same time that the steam is cut off, the piston during a considerable portion of its stroke working against 20 and compressing the steam remaining in front of it in the cylinder after the exhaust-ports have been closed by the valve, which remaining steam offers great resistance to the movement of the piston.

25 The object of my invention is to relieve the cylinder of the steam remaining therein and in front of the piston after the exhaust-ports have been closed, thereby avoiding compression, which I accomplish by providing additional exhaust-ports and a secondary valve controlling such ports, operating substantially as hereinafter fully described.

In the drawings, A represents a steam-cylinder.

35 B is the piston-head, and C the piston-rod. D is a slide-valve located in the steam-chest E. a, a', and b are ordinary steam inlet and exhaust ports.

40 F is a secondary valve, consisting of two parts or heads, c, provided with suitable packing-rings, the two parts c being connected by a central smaller portion, d. This valve F is located in a valve-chamber, G.

45 e e' are two exhaust-passages leading from opposite ends of the cylinder to the valve-chamber G, into which they open at f and g.

h h' are two passages leading from the passages e e', respectively, to the opposite ends of the chamber G, for the purpose of admitting steam to such chamber to operate the valve F.

50 H is an exhaust-port for the valve-chamber G.

I is a bridle upon one end of the valve-chamber G.

J is a rod connected with the valve F, passing through a stuffing-box at one end of the chamber G. Upon this rod are adjustable nuts i and two pieces of rubber or other elastic material, j, one upon the outside and the other upon the inside of the outer end of the bridle I, for the purpose of arresting the movement of the valve F at the proper moment and preventing the valve from striking against the ends of its chamber.

To prevent the valve F from turning in its 65 chamber, the connecting-piece d of the valve may be provided with a slot, k, and a bolt may be passed through the valve-chamber and such slot k.

When steam is first admitted at either end 70 of the cylinder, and before the position of the valve F has been changed in its chamber, live steam can pass for a moment into the valve-chamber G. To prevent waste of steam, I provide the port H with a check-valve, l, which spring is 75 held open by a spring, m, which spring is sufficiently strong to prevent the valve l from being closed by the exhaust-steam, but not sufficiently strong to resist the action of live steam which may pass into the valve-chamber G; 80 hence when live steam does pass into such chamber its pressure will close the valve l and prevent waste. As soon as the position of the valve F has been changed the passage of live steam to the chamber G will be cut off, and 85 then the spring m will open the valve l, allowing the exhaust-steam to escape.

The operation is as follows: Suppose the piston to be moving in the direction of the arrow, steam having been cut off, and the exhaust-port 90 a' being closed by the valve D, the valve F at the same time having been brought to the position shown in Fig. 1 by the action of steam admitted to the valve-chamber through the passage h, the parts being in this position, the exhaust- 95 passage e', leading into the valve-chamber G, will be open, and the steam remaining in the cylinder in front of the piston will pass out through the exhaust-passage e' and through the valve-chamber G, and out at the exhaust-port H. When the piston has completed its stroke, and the passage a' is opened for the admission of steam to the cylinder, the passage a will, as usual, be open as an exhaust, and 100

steam passing to the cylinder through the passage a' will also pass up through the passage h' to the right-hand end of the chamber G and force the valve F over to the opposite end of 5 such chamber, closing the passage f and opening the passage g , and then the steam from the left-hand end of the cylinder, after the exhaust-port a has been closed, will pass out through the passage e into the chamber G and out at 10 to the exhaust-port H . In this manner the engine will be relieved from the labor of working against and compressing the large quantity of steam remaining in the cylinder in front of the piston after the usual exhaust-passages 15 have been closed.

If desired, the movement of the slide-valve D can be so adjusted that steam will be admitted to the cylinder just before the piston reaches the end of its stroke, which admitted 20 live steam will serve the purpose of a cushion.

As shown, the exhaust-passages $e e'$ communicate with the passages $a a'$; but such passages $e e'$ might be made to communicate with the cylinder at any other suitable point. The 25 size of the passages $e e'$ and $h h'$ must be adapted to the engine with which they are to be used. $h h'$ may be considerably smaller than $e e'$.

I do not limit myself to the precise arrangement of the parts which is shown in the drawings, nor to the exact construction shown. 30

What I claim as new, and desire to secure by Letters Patent, is—

1. In combination with a steam-cylinder provided with a valve and inlet and exhaust passages, as usual, a secondary valve located in a 35 chamber provided with an exhaust-outlet, and passages $e e'$ leading from the cylinder to such secondary valve-chamber for the purpose of allowing steam to exhaust from the cylinder after the ordinary exhaust-port has been closed, 40 substantially as and for the purpose specified.

2. In combination with a steam-cylinder provided with a valve and inlet and exhaust passages, as usual, a secondary valve located in a chamber provided with an exhaust-outlet, 45 and passages $e e'$, leading from the cylinder to such secondary valve-chamber, and passages $h h'$, leading from the cylinder to the ends of the secondary valve-chamber, substantially as and for the purposes specified.

AARON A. ACKERLY.
